UNITED STATES PATENT OFFICE.

JOHN CARTER, OF SPARKBROOK, ENGLAND, ASSIGNOR TO THE WEBLEY AND SCOTT REVOLVER AND ARMS COMPANY LIMITED, OF BIRMINGHAM, ENGLAND.

DOUBLE-BARRELED SMALL-ARM.

No. 807,241.

Specification of Letters Patent.

Patented Dec. 12, 1905.

Application filed July 24, 1905. Serial No. 270,982.

To all whom it may concern:

Be it known that I, JOHN CARTER, foreman of department, a subject of the King of Great Britain, residing at 182 Walford road, Sparkbrook, near Birmingham, England, have invented certain new and useful Improvements in Double-Barreled Small-Arms, of which the following is a specification.

This invention has relation to double-barreled sporting-guns and other small-arms, and has for one of its objects to provide such guns with a novel construction of lock mechanism having two distinct triggers which are each capable of both a single and a double action—that is to say, each trigger can have a single action for firing its corresponding barrel only or it may have a double action in which it is adapted to operate the sears pertaining to the separate locks of the two barrels in succession, the order of firing the said barrels being dependent upon the particular trigger selected and used in shooting, so that a sportsman may at his option by pulling the right-hand trigger only as a double-acting one discharge the right barrel first, followed by the left barrel, or by using the left-hand trigger as a double-acting one fire the left barrel first, followed by the right barrel. Thus the shooter may either use the gun in the same way as an ordinary two-trigger one, or he may discharge both barrels in rapid succession and in either order by selecting and operating one of the triggers only and without shifting his finger from one trigger to the other, and consequently disturbing his aim, and thereby all the advantages of selective single-trigger mechanisms may be obtained without their unreliability and other attendant disadvantages.

A further object of the invention is to so arrange the said selective duplex-trigger mechanism that after the first discharge the pulling of either trigger will positively insure the discharge of the remaining loaded barrel, so that in the event of a considerable interval of time elapsing after the firing of the first barrel it will not be necessary for the sportsman to have to remember by which particular trigger the first shot was fired in order to insure the pulling of the correct trigger for obtaining the second discharge.

A still further object is to provide in conjunction with the said mechanism an automatic safety device or interceptor which operates in common upon both triggers and the

parts connected therewith for the purpose of preventing unintentional discharge of the second barrel by the involuntary pull or pressure which is exerted by the shooter's finger upon the trigger employed as a consequence of the recoil set up by the firing of the first barrel.

Figure 1 of the accompanying drawings represents an elevation of the left-hand side of a double-barrel hammerless sporting-gun with the stock and side plates removed, the same being fitted or provided with a selective duplex-trigger-lock mechanism constructed and arranged in accordance with my invention, and in which, furthermore, the trigger-coupling device is so formed and mounted that it will also serve as a means for automatically preventing the unintentional discharge of the second barrel by the involuntary pull exerted upon the trigger as a consequence of the recoil from the first discharge. In this view the several parts of the said lock mechanism are shown in the positions which they assume when both hammers of the gun are cocked ready for firing, but before the "safe" is taken off to allow either of the triggers to be pulled. Fig. 2 is a view showing the right-hand side of the gun with all the parts in the same positions as shown in Fig. 1. Fig. 3 is a sectional elevation of the mechanism in which the blade of the left-hand trigger is broken away, so as to show more clearly the disposition and arrangement of the sliding clutch or trigger-coupling while the safety has been pushed off, so as to leave both triggers free to be pulled at the shooter's option. The coupling-slide is also caused to assume the position in which it is represented in this view by the recoil set up by the discharge of the first barrel. Fig. 4 shows the positions in which the parts are placed when the left-hand trigger is pulled first for discharging the left barrel in advance of the right barrel and just before the sear-nose is taken out of bent with the hammer. Fig. 5 is a view showing the positions which the parts of the mechanism are caused to assume by the action of the involuntary pull after the first discharge—that is to say, it indicates how the two triggers are coupled together by the sliding clutch device, which is placed (as will be hereinafter fully described) by the action of the recoil from the first discharge in an inoperative or intermediate position with respect

to the triggers and is there momentarily retained by a spring-catch device which is, however, immediately freed or disengaged by the movement made by the operated trigger 5 under the effect of the involuntary pull, and the clutch is then taken into coupling engagement with the two triggers by means of its own spring, as shown in this said Fig. 5, so that whichever trigger is next pulled will 10 actuate the second sear and fire the second barrel. Fig. 6 shows the positions of the parts when the two triggers have been coupled together and they are lifted in unison by the pulling of one or other of them for 15 firing the second barrel. Fig. 7 shows an elevation and a top side plan of the trigger-coupling slide upon an enlarged scale.

The same reference-numerals are used to indicate corresponding parts in the several 20 figures of the drawings.

In the mechanism represented in the said drawings the blades 10 11 of the right and left hand triggers 12 13 are independently pivoted to the opposite sides of a lump or projection 14, carried by the bottom strap of the gun, and are each capable of being used either as single or double acting triggers, as hereinafter described. The tails 15 16 of the sears 17 18, pertaining to the right and left hand 25 locks, are arranged to lie, respectively, upon the top edges of the said blades, so that when either trigger is raised its sear will be actuated and the corresponding barrel discharged. Located within the space between the two trigger-blades and normally resting upon the bottom strap is a trigger-coupling plate or clutch-slide 19, which is capable of both a sliding movement and a tilting or rocking motion under the influence of certain other elements of the mechanism, as hereinafter described; but it is nevertheless loosely or freely mounted upon the 30 said bottom strap—that is to say, it is not positively connected to any other part of the mechanism—so that it is adapted, by virtue of its own inertia, to change its position or be subjected to a longitudinal displacement relative to the whole of the other parts of the gun when the latter rebound collectively under the influence of the recoil from a 35 charge. In order to augment the inertia of the said loose clutch-plate, its after end is weighted at 20, while to provide for its longitudinal and angular movements without interfering with its freedom of action under re- 40 coil its forward end has a rounded head or fulcrum 21, which engages within a slot 22 in the base of the lump 14 and is free to rock and also to slide in both directions therein. The said clutch-plate is provided on its oppo- 45 site sides with studs or lateral projections 23 24, adapted to engage, respectively, with gaps or locking-notches 25 26, cut in the after parts of the right and left hand trigger-blades for the purpose of coupling the two triggers to- 50 gether after the first barrel has been dis-

charged and the effects of the involuntary pull have been neutralized; but normally, or when both hammers of the gun are cocked ready for firing, the plate is maintained in its forward position (as represented in Figs. 1, 2, 3, and 7) and the studs are held clear of the trigger-notches by means of a catch or interceptor device 27 engaging with a stop-shoulder 28. This interceptor consists of a flat spring of sufficient width to overlap both the 75 clutch-plate and the blades of the two triggers, and it is mounted at one end on the summit of a fixed post 29, while the other and free end carries a tooth 30, the stop-shoulder with which the said tooth engages 80 being slightly undercut or formed in such a manner that when the spring is lifted by means of one or other of two upright extension-pieces 31 32 of the trigger-blades it will raise the clutch-plate with it, and thus take 85 the studs on the said plate out of their normal alinement with the corresponding locking-notches in the trigger-blades. The interceptor holds the clutch-plate in its forward position in opposition to the force exerted in a 90 rearward direction by a light spring 33, arranged in rear of the lump 14, to which one end is fixed, while the other end is free and bears against the front edge of the clutch-plate. This spring is capable of sliding the 95 said plate rearward and engaging its studs with the locking-notches in the trigger-blades when the plate itself is freed from the retaining-catch; but, on the other hand, the force which it exerts is so slight that it offers no 100 obstacle to the relative displacement of the said clutch-plate by virtue of its own inertia when the gun recoils. The loosely-mounted clutch-plate, in addition to coupling together 105 the triggers, is also utilized in conjunction 110 with its retaining-catch or interceptor as the means for preventing the unintentional firing of the second barrel by the involuntary pull which follows the first discharge, its action 115 in this respect being hereinafter fully described in dealing with the sequence of operations involved in the firing of the two barrels. For the purpose of disassociating or uncoupling the two triggers and restoring 120 the whole of the parts to their normal positions after one or both of the barrels have been fired the rocking safety-limb 34 is also utilized as a resetting device, which acts upon the clutch-plate and pushes same forward 125 when the top lever 35 is actuated for unbolting the gun prior to opening same. This limb is pivoted to the top of the lump 14, and its upper end is engaged with an ordinary slide 36, which is connected with the top lever in the usual way and is pushed backward 130 when the said top lever is operated, while its lower end 37 is adapted, when the gun is at safe, to overlap the inclines 38 on the trigger-blades, and so render it impossible for either trigger to be pulled until the safety- 135

limb has been moved clear of same by pushing the slide forward. The resetting of the clutch-plate is accomplished by the said safety-limb in its forward swinging motion striking against a shoulder 39 on the said plate.

Operation: When the gun is closed after loading, the several parts of the lock mechanism are placed in the positions in which they are shown in Figs. 1, 2, and 3. The toe or lower end 37 of the safety limb rests upon the top inclines 38 of the trigger-blades and also bears against the resetting-shoulder of the clutch-plate, which is held in its inoperative position by the tooth 30 of the interceptor device engaging its stop-shoulder 28. By now actuating the safety-slide the limb 34 is rocked and its toe is swung rearward and clear of the trigger-blades and the clutch-plate, as represented in Fig. 3, and the gun is then in a condition for firing either barrel first at the shooter's option and according as to whether he pulls the right trigger before the left or the left trigger before the right one, so the initial discharge will take place in the corresponding barrel. Assuming that the shooter elects, therefore, to fire the left barrel first, he pulls the left-hand trigger, whose blade acts upon the sear-tail 16 and actuates the sear 18 so that the left-hand hammer is released and fires the cartridge in the selected barrel; but simultaneously with this operation the upright extension-piece 32 is caused by the lifting of the trigger-blade to act against the interceptor-spring 27 and raise the same into the position shown in Fig. 4 in advance of the actuation of the sear and before the discharge can take place, and by reason of the interlocking engagement of the interceptor-tooth 30 and the stop-shoulder 28 the elevation of the said interceptor also constrains the clutch-plate to make an upward angular movement upon its fulcrum end. This takes the studs of the clutch-plate out of their normal alignment with the locking-gaps in the trigger-blades and places all the parts in the positions shown in Fig. 4. The discharge of the left barrel now takes place, and the recoil throws back the whole of the gun against the shooter's shoulder, less the clutch-plate, which by virtue of its loose mounting and its inertia, augmented by the weighted after end 20, makes a relative forward movement, so that instead of the said clutch-plate escaping from its retaining-catch and moving rearwardly under the influence of the spring 33 into the position in which it couples together the triggers the tooth 30 comes again into full engagement with the stop-shoulder 28, as shown in Fig. 3, and thus the clutch-plate is caught or intercepted and held in the same position with respect to the trigger-blades as it assumed before the trigger was pulled. The forward rebound of the gun from the shoulder which follows the recoil jerks the trigger

against the shooter's finger and causes the involuntary pull, which is utilized in disengaging the interceptor from the clutch-plate, so as to allow same to be taken rearward by its spring into coupling engagement with the 70 trigger-plates. Thus the effect of the involuntary pull upon the trigger is such as to lift the interceptor-tooth quite clear of the stop-shoulder 28. The spring 33 then drives the clutch-plate rearwardly, and immediately 75 the operated trigger has been fully lowered, so as to bring both locking-notches of the trigger-blades into alignment with the studs 23 24, the said studs pass into engagement with the said notches and are there retained 80 by the pressure of the said spring 33, assisted also by the interceptor, whose tooth now bears upon the incline forward of the shoulder 28, as represented in Fig. 5. The two triggers are thus coupled together by the clutch-plate 85 so that these three elements can only move collectively or in unison, as shown in Fig. 6, and the firing of the next barrel—i. e., the right-hand one—can be effected either by pulling the left-hand trigger again or by shifting 90 the finger onto the right-hand trigger and pulling that one. Whichever trigger is utilized, the blade of the left-hand is made to act upon the tail of the left-hand sear and fire the corresponding barrel. After both barrels 95 have been discharged, the manipulation of the top lever for undoing the bolt of the gun forces the safety-slide rearwardly in the usual manner, and this has the effect of rocking the safety limb, whose toe 37 in swinging forward impinges against the resetting-shoulder 39 and carries the clutch-plate with it, thus disengaging the studs 23 24 from the notches 25 26 and disassociating the triggers from one another and at the same time bringing 100 the shoulder 28 once more in front of the tooth of the interceptor, so that after the gun has been opened to recock the hammers and then closed the sequence of operations is completed and the whole of the parts are restored 105 again to the normal positions shown in Figs. 1 and 2, ready for firing.

Having fully described my invention, what I desire to claim and secure by Letters Patent is—

1. In selective duplex-trigger mechanism for double-barrel guns; the combination with two separate triggers each adapted to directly actuate the sear of the corresponding barrel when pulled for obtaining the first discharge, of a sliding clutch-plate or coupling adapted to be engaged, by a spring, with the trigger-blades for connecting them together after the first discharge; means being also provided for holding the clutch or coupling out of engagement with the trigger-blades until after the first shot has been fired, for preventing accidental or unintentional discharge of the second barrel by the involuntary pull set up by the recoil from the first discharge, and for 130

disengaging and resetting the clutch device after each discharge of one or both barrels, substantially as herein described.

2. In selective duplex-trigger mechanism for double-barrel guns, the combination with two separate triggers whose blades are each adapted to act directly upon its sear when the corresponding trigger is pulled for firing the first barrel and which are clutched or coupled together after the first discharge so that the pulling of either trigger will then fire the second barrel, of a free or loosely mounted and weighted clutch-slide, provided with a spring which tends to engage same with the trigger-blades, and an interceptor which normally holds the said slide out of engagement with the said blades and is disconnected therefrom by the pulling of either trigger, and is also adapted to admit of the relative movement of the said slide by virtue of its own inertia when the gun recoils; the several parts operating in such a manner that the clutch cannot be moved into coupling connection with the trigger-blades until the involuntary pull following the recoil from the first discharge has been utilized to disengage the interceptor from the said slide, substantially as herein described and also as set forth in the drawings.
3. In a selective duplex-trigger mechanism for double-barrel guns, the combination with the two triggers or trigger-blades and a clutch device for connecting together and disconnecting said triggers of a combined safety limb and resetting device adapted to disengage the clutch and restore same to its normal or inoperative position when the bolt-lever of the gun is moved, substantially as herein described and set forth.
4. A duplex-trigger mechanism for double-

barreled guns having trigger-blades, movable means for automatically coupling together the said trigger-blades, means for controlling the movement of the said coupling means, means for resetting the latter to its normal inoperative position, and a safety element co-operative therewith for locking the trigger-blades.

5. A duplex-trigger mechanism including trigger-blades, a movable element for automatically coupling said blades and for releasing the same, means for resetting said coupling element, and a safety device operated by the resetting means for locking the said trigger-blades.

6. A duplex-trigger mechanism having a movable coupling element, an interceptor controlling the displacement of the said coupling element, and means for returning the said coupling element to a normal inoperative position and for locking the triggers.

7. In a duplex-trigger mechanism, pivotal trigger-blades separated from one another, a movable coupling element interposed between the blades, a resetting device for returning the said coupling element to an inoperative position, a safety limb actuated by the resetting device for locking the said blades, and a yieldable interceptor arranged within the path of movement of the said coupling element for controlling the movement of the same.

In testimony whereof I have hereunto set my hand in presence of two subscribing witnesses.

JOHN CARTER.
